SHEARHEAD FOR DRY SHAVING APPARATUS

Paul Kobler, Lynbrook, N. Y., assignor to Victor Kobler and Werner Kobler, both of Zurich, Switzerland

Application July 9, 1952, Serial No. 297,945

5 Claims. (Cl. 30—43)

The present invention relates to a shearhead for dry shaving apparatus which shearhead comprises a hollow outer member and an inner cutter member located with said outer member and movable relative thereto, said outer member having openings extending therethrough for passage of hairs to the inner cutter member to be cut thereby, the outer cutter member being so formed that part of its outer surface is higher than other parts and thus presses more strongly against the skin being shaved, at least some of said openings in said higher part being bordered by sharp edges. The shearhead preferably has a transversely slotted hollow outer cutting member and a transversely slotted inner cutting member reciprocable within and longitudinally of said outer cutting member for cooperation therewith. More particularly, this invention relates to a shearhead of the said kind in which the said outer cutting member, which may be straight or curved in longitudinal profile, has two inner surfaces defined, in transverse section, by a pair of straight lines intersecting each other at an obtuse angle and two outer surfaces defined, in transverse section, by straight lines parallel to those defining the said inner surfaces.

As well known in the art, it is desirable in such shearheads that the thickness of the outer cutting member, that is, the distance between the said parallel outer and inner surfaces thereof be as small as consistent with an adequate strength of the cutting member, in order to ensure that a close shave can be obtained. In the region of the oblique intersection of the two inner and the two outer surfaces, however, the outer cutting member of such shearheads has a thickness which is greater than that between the parallel inner and outer surfaces, and greater than required for warranting sufficient strength, so that the closeness of the shave is unnecessarily impaired in the said region of the outer cutting member where the said member is highest and presses most strongly against the skin being shaved.

It is one of the objects of the present invention to avoid this drawback and to provide a shearhead in which the thickness of the outer cutting member in the said region is made as small as desirable.

Other objects and advantages of the invention will become apparent from the description now to follow of a preferred embodiment thereof, in which reference will be had to the accompanying drawing, in which:

Fig. 1 is a longitudinal section of a shearhead according to the invention;

Fig. 2 is a partial plan view of the shearhead of Fig. 1 at an enlarged scale;

Fig. 3 shows in perspective part of the shearhead, with portions thereof cut away to show its transverse section;

Figs. 4 and 5 show at an enlarged scale partial cross-sections along lines IV—IV and V—V, respectively, of Fig. 2.

Figs. 6, 7 and 8 are partial longitudinal sections, taken on lines VI—VI, VII—VII and VIII—VIII, respectively of Figs. 4 and 5 and showing at an enlarged scale certain details of the outer cutting member;

2

Fig. 9 is a cross-section analogous to that of Fig. 4 but referring to an alternative embodiment;

Figs. 10 and 11 are partial plan views of other alternative embodiments; and

Fig. 12 is a plan view of the arrangement of the shearheads on a shaving apparatus having three shearheads.

As shown in Figs. 1 to 8, the shearhead of a dry shaving apparatus comprises a base piece 1 mounted by sockets 2 on the housing 3 of the apparatus. This base piece carries an outer cutting member 4 which is in the general form of a longitudinally arched inverted U-shaped channel and the parallel flanges of which are riveted at 5 to the base piece 1. In its top portion, the outer cutting member is provided with a series of equidistant transverse slots 6 leaving between them small bridges 7.

The base piece 1 has a longitudinal groove 8 guiding an inner cutting member 9 in the shape of a ring segment having an enlarged rim into which are cut equidistant transverse slots 11 leaving between them a series of teeth 12. The top face of these teeth 12 conforms to the inner face of the bridges 7 left between the slots 6 and is wider, in the longitudinal direction of member 9, than the said slots so that the teeth 12 cannot engage the slots 6 and the inner cutting member 9 is maintained in its guiding groove 8 by the outer cutting member but capable of longitudinal motion along the latter's inner face. Moreover, the inner cutting member has a recess 13 engaged by an actuating lever 14 extending through a wide opening 15 in the base piece 1. This actuating lever is pivoted on a pin (not shown) in the housing 3 and in operation is oscillated by an electric motor and suitable transmission means (not shown) lodged in the said housing. Thus, the inner cutting member 9 will be reciprocated along the inner face of the outer cutting member 4 and any hair which extends into the slots 11 through the slots 6 when these slots register will be shorn off between the adjacent bridge 7 and tooth 12 as the inner cutting member 9 moves with respect to the outer cutting member 4.

Referring now particularly to Figs. 4 and 5 which show transverse sections of the top portion of the outer cutting member 4, taken at various points thereof, the said outer cutting member 4 has two inner surfaces 17 defined and represented by a pair of straight lines intersecting each other at 18, at an obtuse angle. Further, the outer cutting member has two outer surfaces 19 also represented or defined by a pair of straight lines which are parallel to those representing the inner surfaces 17. In Fig. 5, which is a cross-section taken through an end portion of member 4, the lines indicating the surfaces 19 intersect each other at 20, which indicates an obtuse edge along which the surfaces 19 meet each other.

In the central portion of member 4, however, the surfaces 19 do not meet but there is between them a third surface which may have various shapes as seen in transverse section. As shown in Fig. 4, this third outer surface 21a is defined by an arc of circle the center of which is at 18, where the inner surfaces 17 of the member meet each other. Accordingly, the thickness of the outer cutting member is the same everywhere, whether measured between the surfaces 17 and 19 or between the edge 18 and the surface 21a. Fig. 9 represents an alternative shape of said surface which, in this case, is represented in transverse section by a straight line 21b. Preferably, the distance between the surface 21a and the said point 18, and accordingly the thickness of the outer cutting member in this region, is at most equal to that between the inner and outer surfaces 17 and 19, respectively. It will be understood that all the surfaces 17, 19 and 21a as well as their edges 18 and, where present, 20, are interrupted from place to place by the slots 6 and in fact appear only on the bridges 7; nevertheless, they will be referred to for

the convenience of the description, as if they were continuous.

Figs. 6 to 8 are enlarged cross-sectional views taken longitudinally of the shearhead through various portions of the outer cutting member to show the cross-section of the bridges 7. Fig. 6 represents a normal cross-section through three bridges 7 and applies both to the longitudinal portion of the outer cutting member the transverse section of which is shown in Fig. 4, and the longitudinal portions shown in transverse section in Fig. 5. It will be seen from Fig. 6 that those outer edges 22 of the bridges 7 where the slots 6 meet the portions of the outer surfaces designated 19 are rounded, while the edges 23 of said bridges where slots 6 meet the inner surfaces 17 are sharp; these sharp edges 23 being, in fact, the cutting edges of the outer cutting member.

Fig. 7 is an enlarged longitudinal cross-sectional view of the outer cutting member, showing three bridges 7 in cross-section and applying only to the end portions, having the transverse section shown in Fig. 5. Fig. 7 differs from Fig. 6 in that its plane passes through the edges 18 and 20 (Fig. 5), that is, obliquely with respect to the surfaces 17 and 19. Therefore, the height of the bridges 7 is greater in Fig. 7 than in Fig. 6, but otherwise the two figures are identical especially in that the outer edges of the bridges are rounded at 22 and the inner edges thereof are sharp as at 23.

Fig. 8 is a longitudinal section similar to that of Fig. 7 but taken in the central portion of member 4 to which Fig. 4 applies. The height of the bridges 7 in this section, which is the distance between the surface 21a and the edge 18, therefore is smaller than in Fig. 7. In the particular embodiment shown, in which the surface 21a is defined by an arc of circle the center of which is on edge 18, the height of the bridges 7 in the section according to Fig. 8 is equal to that in the section according to Fig. 6. In alternative embodiments, however, such as that shown in transverse section in Fig. 9, the said height of the bridges, that is, the distance between point 18 and the center of surface 21b is smaller in the section according to Fig. 8 than in that according to Fig. 6.

As shown in Fig. 8, the edges 24 of the bridges 7 at which the slots 6 meet the outer surface 21a are sharp. This will conveniently be achieved by first grinding the surfaces 19 and the slots 6 with their common rounded edges 23, throughout the length of the cutting member 4, to the shape indicated in Figs. 5, 6 and 7 required for the end portions of the member and indicated in dash-and-dot lines in Fig. 8. Thereupon, the surface 21a is ground in a second operation whereby the material in excess including the rounded edges 22 is removed so as to provide the sharp edges 24.

Longitudinally of the outer cutting member 4, the said surface may be carried out in various shapes. As particularly shown in Figs. 1 and 2, the surface is ground to the same depth over a central portion of the length of member 4, including a certain number of bridges 7 for which the transverse profile of the cutting member corresponds to either Fig. 4 or Fig. 9. In an alternative embodiment shown in plan view in Fig. 10, the surface 21c has a longitudinal curvature which is less pronounced than that of surfaces 19, or it even may be straight in longitudinal profile. Thus, the depth to which and the width on which surface 21c is ground from the surfaces 19 increases from both ends towards the middle of said surface 21c. Each of the bridges accordingly differs in shape from the adjacent ones, so that the transverse section shown in Fig. 4, or that shown in Fig. 9, applies to only one or two individual bridges 7, with the remaining bridges differing in shape therefrom by having either a wider surface and accordingly smaller height at their apex, or a narrower surface 21c with greater height at their apex than the said one or two bridges.

In still another embodiment, shown in plan view in Fig. 11, the surface 21d extends throughout the length of the cutting member 4, in which case the transverse section

may be as shown in Fig. 4 or in Fig. 9 while at no part is it as shown in Fig. 5.

The described shearhead having an outer surface as shown at 21a, 21b, 21c, or 21d, has the following advantage: In the shaving process, the outer surfaces 19, 21a, 21b, 21c, or 21d of the shearhead are pressed against, or maintained in contact with, the skin of the person to be shaved and the hair extending through the slots 6 will be cut off between the inner cutting member 9 and the outer cutting member 4 at the level of the inner surface 17 of the latter when the inner cutting member is reciprocated. Thus, to obtain a close shave, it is desirable that the distance between the outer and the inner surface of the outer cutting member, that is the height of the bridges 7, be as small in the cutting region as is consistent with a sufficient strength of these elements. Where the transverse section of the outer cutting member is as shown in Fig. 5, it will be noted that in the region of the point 20 the height of the bridges 7 is greater and accordingly the shave less close than in other regions, although such increased height of the bridges 7 is not necessary to give the bridge its required strength. Now, due to the obtuse angle at which the two surfaces 19 are situated, the edge 20 in such transverse section as shown in Fig. 5 is the point at which the surface is highest and pressed most strongly against the skin and the skin is best tensioned and applied to the shearhead so that the optimum shave will occur at this point. If therefore the shave is not close enough at this point, it will be difficult for the user to obtain a close shave at all. This drawback is overcome according to the invention by providing on at least part of the length of the shearhead the described outer surface 21a, 21b, 21c, or 21d which is at a smaller distance from the inner surfaces 17 or their intersection 18 than the edge 20 would be. The provision of this surface 21a, 21b, 21c, or 21d thus materially improves the closeness of the shave. In the embodiment represented in Fig. 4 the distance between said surface 21 and the edge 18 is the same as the thickness of the material between the inner and outer surfaces 17 and 19 respectively, so that the provision of surface 21a, 21b, 21c, or 21d will not affect the strength of the bridges 7. In fact, it may even be admissible to have at this point a smaller thickness of material than in the adjacent regions, so that the surface may still be set a little deeper.

Regarding Figs. 6 to 8, it will be noted that the provision of rounded edges 22 in the region of the outer surfaces 19 favours the bulging of the skin into the slots 6 whereby the shave will be substantially closer than if the skin were tensioned flat over the surfaces 19. If, however, this desirable bulging of the skin were also favoured by rounded edges in the region of the surface 21a, 21b, 21c, or 21d in which the height of the bridges 7 is reduced and the tension of the skin over the apex of the shearhead is increased, the skin might bulge at this point beyond the inner surface 17 of the outer cutting member, become engaged with the teeth 12 of the inner cutting member 9 and be damaged or irritated by them. This is avoided by the provision of the sharp edges 24 of the outer surface 21a, 21b, 21c or 21d, a feature which tends to reduce the bulging of the skin into the slots 6.

Although the intermediate outer surface may be extended to the full length of shearhead as shown in Fig. 11, without departing from the scope of the invention, the provision of end portions not provided with such intermediate surfaces as shown in Figs. 2 and 10 has the advantage that it ensures some additional tensioning of the skin in a longitudinal direction between such end portions, and accordingly a better shave in the region of the surfaces of the intermediate portion of the shearhead in which they are provided.

As shown in Fig. 12, the shaving apparatus may comprise three shearheads 26, 27 and 28, the two outer shearheads 26 and 28 having no intermediate surfaces and the middle shearhead 27 having such surfaces in its longitudinally central portion as described with reference to Figs. 1 to 8. This arrangement ensures that the skin is

tensioned in transverse direction between the shearheads 26 and 28, and in longitudinal direction between the end portions of the shearhead 27 so as to receive its optimum shaving in the central portion of the latter.

While the shearhead shown in the drawing is longitudinally curved, it will be understood that its longitudinal profile could be straight without departing from the scope of the invention.

What I claim is:

1. In a mechanical shaver shearhead, an outer cutter, an inner cutter adapted to be moved relative to said outer cutter in operation, said outer cutter having an outer surface for engaging the skin to be shaved, said cutter surface being formed with a portion thereof at a higher level than other portions so that said higher portion presses against the skin more strongly than said lower portions, said outer cutter having openings extending therethrough to said inner cutter for permitting hairs to pass inwardly to said inner cutter to be cut, the edges of said outer cutter bordering some of said openings being sharp at said portion of said outer cutter which is higher and presses more strongly against the skin, and said edges being rounded at the portions which are lower and press less strongly against the skin.

2. A shearhead according to claim 1 and in which the outer cutter, at the higher portion thereof where the edges of said opening are sharp, is of less thickness than the lower portions where the edges bordering said openings are rounded.

3. A shaver according to claim 1 and in which the openings bordered by sharp edges are arranged in an elongated portion of the outer cutter member extending along a line disposed longitudinally and centrally of said outer cutter member, said elongated portion being bordered on all sides by said portions of said cutter member which are provided with said openings bordered by round edges.

10

15

20

35

4. A shearhead according to claim 1 and in which a portion of the openings bordered by said sharp edges of the outer cutter member are positioned at an area of said outer cutter member which is surrounded on all sides by an area of said outer cutting member which is provided with openings bordered by rounded edges, the thickness of the outer cutter member at the area provided with the openings bordered by sharp edges being less than the thickness at said surrounding area.

5. In a mechanical shaver shearhead, an outer cutter, an inner cutter adapted to be moved relative to said outer cutter in operation, said outer cutter having an outer surface for engaging the skin to be shaved, said outer surface being formed with a portion thereof at a higher level than other positions so that said higher portion presses against the skin more strongly than said lower portions, said outer cutter having transverse slots extending therethrough to said inner cutter for permitting hairs to pass inwardly to said inner cutter to be cut, the edges of said outer cutter bordering said slots being sharp at said portion of said outer cutter which is higher and presses more strongly against the skin, and said edges being rounded at the portions which are lower and press less strongly against the skin.
